[57] CLAIM

The ornamental design for a measurement system display module, as shown and described.

DESCRIPTION

FIG. 1 is a top, front, and right side perspective view of a measurement system display module showing our new design;

FIG. 2 is a front elevational view;

FIG. 3 is a top plan view;

FIG. 4 is a bottom plan view;

FIG. 5 is a right side elevational view;

FIG. 6 is a left side elevational view; and

FIG. 7 is another top, front, and right side perspective view thereof. The broken line showing of guide rails are environmental only and forms no part of the claimed design.

FIG. 1

FIG. 2

FIG. 3

FIG. 4

FIG. 5**FIG. 6**FIG. 7
